UNITED STATES PATENT OFFICE.

HUGH O. AMES, OF NEW ORLEANS, LOUISIANA.

EVAPORATING-PAN.

SPECIFICATION forming part of Letters Patent No. 276,324, dated April 24, 1883.

Application filed December 18, 1882. (No model.)

To all whom it may concern:

Be it known that I, HUGH O. AMES, of New Orleans, in the parish of Orleans and State of Louisiana, have invented a new and Improved 5 Evaporating-Pan, of which the following is a full, clear, and exact description.

This invention pertains to improvements upon my pan for evaporating cane-juice for which Letters Patent No. 235,613 were granted 10 to me December 21, 1880, wherein I employed, in connection with a branched steam-pipe, two series of alternating heating-pipes, with their inner ends provided with downwardly-extended pockets for the condensed steam, from which 15 the condensed steam passed off into correspondingly-constructed condensed steam-pipes connected with a branched discharge-pipe.

The nature of this invention consists in certain 20 novel features of construction and arrangement, having the object to obtain a uniform heating and circulation of the liquid for expediting the evaporation and ridding the liquid of the scums more perfectly and rapidly, as hereinafter described and claimed.

Reference is to be had to the accompanying drawings, forming part of this specification, in which similar letters of reference indicate corresponding parts in all the figures.

30 Figure 1 is a sectional plan view of an evaporating-pan with my improvements. Fig. 2 is a transverse section of the same, and Fig. 3 is a detail view.

E is an evaporating-pan of the usual size 35 and shape.

B is the main steam or stock pipe. C is the condensed-steam pipe, and D D are the evaporating-pipes connected to the pipes B C, the whole forming a horizontal grate 40 within the pan. The ends of the stock-pipe B are fitted to turn steam-tight in the trunnions b b, so that the grate may be turned upward for facility of cleaning the pipes.

A is the main steam-supply pipe, provided 45 with a suitable valve for regulating the inlet of steam, and branched to connect with the stock-pipe B at both the trunnions b, so that when the steam is supplied from the boiler it will pass to both ends of the pipe B, and thence 50 to the evaporating-pipes D, wherein the steam is condensed, and the water flows to the pipe C and out at the outlet a. As shown in Fig. 3, the pipe C is formed with a gutter, d, which is inclined from the ends of the pipe C toward 55 the outlet at the middle. The object of this

inclined gutter is to drain the water from the evaporating-pipe to the lowest point, so as to utilize all the surface of the pipes B for heating purposes.

By supplying steam to the pipe B at both 60 ends a more complete effect in boiling is obtained than where the steam is furnished at one end only of the steam-pipe, for the reason that if steam be supplied at one end only, the heat being greater at that point, the greater 65 part of the scum will be thrown toward the opposite corner diagonally, and the circulation of the liquid is also greatest in the same direction.

With my improvements, the heat being 70 equally distributed across the end of the pan, the circulation in boiling is uniform across the whole body of the liquid and at right angles to the pipe B, so that the scums will be carried toward the pipe C, where they are 75 skimmed off. In this manner all parts of the liquid being boiled are brought into contact with the heat uniformly, the evaporation is thereby hastened, and the scums thrown off more perfectly and rapidly. This is an im- 80 portant advantage, as it reduces the time during which the liquid is subjected to the heat.

When the pan is to be used as a "strike-pan," for concentrating the sirup to the "striking" or sugar point, the grate will be made 85 double—that is to say, two grates will be used, hinged at opposite ends of the pan—and by that arrangement a uniform temperature will prevail over the whole area of the pan, and the whole body of the sirup will be brought to 90 the striking-point simultaneously.

Having thus described my invention, what I claim as new, and desire to secure by Letters Patent, is—

1. In evaporating-pans, the combination and 95 arrangement of the steam or stock pipe B of the grate, and steam-supply pipe A, substantially as described, for supplying steam at both ends of the stock-pipe.

2. In evaporating-pans, the combination of 100 the steam-pipe A, the stock-pipe B, the evaporating-pipes D, and condensed-steam pipe C, substantially as shown and described.

3. In evaporating-pans, the condensed-steam pipe C, formed with the longitudinal gutter d, 105 and combined with the evaporating-pipes D, substantially as described.

Witnesses: HUGH OSWALD AMES.
